GILBERT SANFORD VERNAM, OF RIVER EDGE, NEW JERSEY, ASSIGNOR TO
INTERNATIONAL COMMUNICATIONS LABORATORIES INCORPORATED

TELEGRAPH REPEATER SYSTEM

Application filed November 30, 1929. Serial No. 410,711.

This invention relates to telegraph systems and more particularly to a repeater for single line telegraph systems.

In former single line repeater systems it has been the practice to utilize non-polar relays or combinations of polarized relays. Neutral relays which depend on strength of current for their operation have been found to be too sluggish in their action to be satisfactory for automatic printer systems. Heretofore, the polar type of single line repeater required a minimum of four or more relays and a correspondingly complicated hook-up. Accordingly, this invention has for its object to provide a simple, efficient and less expensive polar single line repeater employing but two standard polar relays in its operation.

In carrying out this invention there is provided at the repeater station a pair of differentially wound polar relays having three separate windings. Two windings of each relay are differentially connected, the second terminal of one coil being connected to ground through an impedance and resistance, the other side of the second coil in each case being connected to the outgoing line. The third coil of each relay is energized by a small current from a local battery of such direction that it always tends to move the tongues of the relays to their right hand or marking contacts.

The apex of the differentially connected coils of one relay is connected to the tongue of the other relay in each case. The tongues of both relays, when the line is closed, rest on their right hand or marking contacts which are connected to one pole of a source of potential; the other pole being grounded. The repeater operates as follows:

Referring to the drawings; A and B indicate the terminals of the telegraph line. The line is divided into two sections 1 and 2 by a repeater station R. There are two polar relays 3 and 4 at R, each having a plurality of windings. Windings 5 and 6 of relay 3 are connected differentially at 7 and likewise windings 8 and 9 of relay 4 are connected differentially at 10. The other terminal of coil 5 of relay 3 is connected to ground at 13 through impedance 11 and resistance 12.

Likewise the corresponding terminal of coil 8 of relay 4 is connected to ground at 16 through impedance 14 and resistance 15. The incoming line 1 from station A is joined to the second terminal of coil 6. Line 2 is connected in the same manner to coil 9. Tongue 17 of relay 4 is connected to coils 5 and 6 at their apex 7. Tongue 18 of relay 3 is connected to the coils 8 and 9 of relay 4 at 10. Contact 19 of relay 3 is connected through resistance 20 to a source of potential 21 which is grounded at 22. Contact 23 of relay 4 is connected through a resistance 24 to a source of potential 25 which is grounded at 26. Each relay has a coil 27 which is constantly energized from a battery 28 through a resistance 29. There is only a light current flowing through the coils 27 and its direction is such that it constantly tends to move the tongues 17 and 18 over to their marking contacts 19 and 23. At station A, 34 indicates an ordinary Morse key and 36 a relay. At station B, 35 and 37 indicate similar apparatus, though of course it is understood that suitable automatic printer apparatus might be substituted.

In the invention in its preferred form windings 5 and 6 of relay 3 and windings 8 and 9 of relay 4 each have a resistance of 85 ohms. Windings 27 of relays 3 and 4 each have a resistance of 300 ohms. The constants of the circuit are so arranged that with the keys 34 and 35 closed, current of about .060 ampere flows in coil 6 of relay 3 and in coil 9 of relay 4. Approximately .035 ampere flows through coil 5 of relay 3 and coil 8 of relay 4. About .025 ampere flows through the coils 27 of relays 3 and 4 but these coils have fewer turns than the other coils and this current is about equivalent in its effect to .005 ampere in the coil similar to the others just referred to. Since coils 6 and 27 of relay 3 aid each other and their pull is opposite to coil 5, the net result is equivalent to a current of .030 ampere in a single coil acting in the same direction as coil 6. When no current flows through coil 6, then coil 5 will move the relay tongue to the opposite contact owing to its pull of .035 ampere overcoming the constant marking pull of .005 ampere of 100

coil 27. Relay 4 is operated in the same manner.

With the keys at both stations closed and considering the circuit from station A, the current flows from positive battery 25 through resistance 24, contact 23 and tongue 17 of relay 4 to the junction 7 of coils 5 and 6 of relay 3 where part of the current goes through the coil 5, the impedance coil 11 and resistance 12 to ground at 13. The larger part of the current in battery 25, however, goes through coil 6, the relay 36, and the key 34 at station A to ground. The armature of relay 3 is held to its marking contact 19 due to the pull of coil 6 which is stronger than that from coil 5 which tends to move the armature in the opposite direction. On opening the key at station A the circuit will be opened through coil 6 only, and the tongue of relay 3 will be pulled to its spacing contact 30 while the relay 36 at station A is also released. The armature of relay 4 will remain against its marking contact 23 when the circuits through coils 8 and 9 are both opened at contact 19 of relay 3, because of the tendency of coil 27 of relay 4 to hold tongue 17 on contact 23. When the circuit through coil 9 is opened the relay at station B is also released, that is, opening the key at station A releases the armatures of the relays at stations A and B.

Upon closing the key at station A, the circuit is restored from point 7 of relay 3 through coil 6 through the relay and key of station A to ground, thus operating the relay at that station and also moving the tongue of relay 3 back to contact 19. When tongue 18 makes with contact 19 the circuit through coil 9 of relay 4 will be restored and relay 37 at station B will be operated. A signal from station B would be repeated through relay 4 in a similar manner as from station A to B, except that relay 4 would operate instead of relay 3. If the key 35 at station B were opened while the key at station A was open, no effect would be noticed at station A because line 2 is already open at the tongue 18 and the contact 19 of relay 3, and relay 4 is held to its marking contact 23 by the current in coil 27 as explained above. If the key at station A is subsequently closed and the key at station B remains open, the relay 3 will go back to its marking contact 19 and relay 4 will be operated by the current through its winding 8 to repeat the break signal to station A. Station A then cannot send because line 1 is open at the tongue 17 and the contact 23 of relay 4.

Inductances 11 and 14 are placed respectively in series with coil 5 of relay 3, and coil 8 of relay 4, and grounded resistances 12 and 15 in order to compensate for the inductance of the distant relay, so that when the circuit through the differentially connected coils of one relay is closed by the tongue of

the other relay going to marking, the current in the coil 5 or 8 of whichever relay happens to be energized will not build up faster than the coil with which it is differentially associated and thus pull that relay to spacing. 70

What is claimed is:

1. In a single line repeater a pair of relays, each relay being provided with three windings and two of which are adapted to exert a pull in one direction and the third in the opposite direction. 75

2. A telegraph repeater comprising a pair of polar relays each having a continuously energized biasing winding and a pair of differential windings; said differential windings 80 being in unbalanced circuits.

3. A telegraph repeater comprising a pair of polar relays, each having a continuously energized winding and a pair of differential windings, said differential windings being 85 in unbalanced circuits, and said continuously energized winding being adapted to aid one of said differential windings and to oppose the other of said windings.

4. A telegraph repeater comprising a pair of polar relays, each having a continuously energized winding and a pair of differential windings, said differential windings being in unbalanced circuits, one of said differential windings being adapted to control said relay 90 on a closed line signal and the other being adapted to control said relay on an open line signal.

5. A telegraph repeater comprising a pair of line relays, each of said relays having a 100 continuously energized winding and a pair of differential windings, said differential windings being in unbalanced circuits, one terminal of one of said differential windings being connected to the associated line section, and the other terminal of said winding and a terminal of the other differential winding being connected to a contact of the other line relay. 105

6. A telegraph repeater comprising a pair of line relays, each of said relays having a 110 continuously energized winding and a pair of differential windings, said differential windings being in unbalanced circuits, and one of said differential windings being alone 115 opened on open line input signals.

7. In a signalling system, a telegraph line divided into sections, and means comprising a single source of a single potential and a single polar relay associated with each section for repeating signals from one into another of 120 said sections.

8. A telegraph system comprising a pair of line relays, each responsive to input signals and irresponsive to output signals, said relay 125 each having a continuously energized winding and a pair of differential windings, said differential windings being in unbalanced circuits, and means responsive to the operation of one of said line relays for rendering the other line relay irresponsive by opening both 130

the differential windings of said relay when the responsive line relay operates in one direction and by closing both the differential windings of said relay when the responsive line relay operates in the other direction.

9. A telegraph repeater having a pair of polar relays each possessing a pair of normally energized differential windings and a continually energized bias winding.

10. In witness whereof, I hereunto subscribe my name this 27th day of November, 1929.
